UNITED STATES PATENT OFFICE.

WILLIAM J. NESBITT, OF LOS ANGELES, CALIFORNIA.

HEEL-CLAMPING MEANS.

1,170,179.

Specification of Letters Patent.

Patented Feb. 1, 1916.

Application filed September 27, 1915. Serial No. 52,957.

To all whom it may concern:

Be it known that I, WILLIAM J. NESBITT, a citizen of the United States of America, residing at Los Angeles, county of Los Angeles, State of California, have invented a certain new and useful Heel-Clamping Means; and I do hereby declare the following to be a full, clear, and exact description of the invention, such as will enable others skilled in the art to which it appertains to make and use the same.

This invention relates to heel cutting apparatus; more particularly to improvements in the means for gripping or clamping the heel so that the heel is held firmly in position while it is moved past the saw or other cutter to cut away a part of the heel.

The main object of the invention is to dispense with the heel abutment heretofore used, and simplify the heel clamping means to permit of the heel being clamped by a single operation.

Other objects and the advantages of the invention will be apparent to those skilled in the art from a careful consideration of the following description, taken in connection with the accompanying drawings in which—

Figure 1 is an elevational view showing a portion of the heel cutting apparatus with the improved heel clamping means; Fig. 2 is an enlarged broken sectional view taken on the line 2—2 of Fig. 1; Fig. 3 is an enlarged broken sectional view taken on the line 3—3 of Fig. 1; and Fig. 4 is an enlarged broken elevational view of a portion of the heel clamping means.

The improved heel clamping means may be used in connection with any suitable form of heel cutting apparatus, or those forms disclosed in my patents dated Sep. 1, 1914, Nos. 1,109,137, and 1,109,139.

Any suitable means may be employed for adjusting and moving the shoe 5 relatively to the cutter or saw 6. The means shown in this instance consists of the platform 7, the table 8, movably mounted on the platform 7 to carry the shoe 5 past the cutter 6, and the table 9 to adjust the shoe laterally of the cutter 6 so that the desired part of the heel 10 of the shoe 5 may be cut off by the cutter 6.

The improved heel clamping means consists of the lower plate 11 and the upper plate 12 which are disposed in substantially the same vertical plane and have the adjacent edge portions 13 thereof curved and

adapted to fit in the crease 14 between the heel seat 15 and the heel 10 of the shoe 5. The lower plate 11 is stationarily mounted, being affixed to the table 9 by the screws 16 in this instance, and the upper plate 12 is secured to the pivotally mounted lever 17 by bolts 18 or other suitable means. As shown, the lever 17 may be provided with a handle 19 on the forward part thereof, and it has on its rear end the pivot 20 which is adapted to fit in any one of the spaced openings 21 provided in the upper part of the post 22 which is mounted at the rear of the table 9. On one or both of the plates 11 and 12 is provided a lateral projection or ledge 23 which is disposed adjacent to the curved edge portion 13 and is substantially parallel to the curved edge portion 13. The projection 23 has arranged longitudinally thereon a row of pins or teeth 24 whose pointed ends 25 terminate short of the edge of the curved edge portion 13 so as not to interfere with the latter being quickly placed in the crease 14.

From the foregoing the manner of use and the advantages of the invention will be evident to those skilled in the art, it being understood that the shoe 5 is placed on the lower plate 11 to have the edge portion 13 of the latter fitted in the crease 14, and then the lever 17 is moved downwardly to have the edge portion 13 of the upper plate 12 fitted in the crease 14. When the lever 17 is pulled down the edge portions 13 fitted in the crease 14 prevent sidewise movement relatively to the cutter 6, and the teeth 24 are pressed into the heel 10 adjacent to the heel seat 15 and they act effectively to prevent forward movement relatively to the cutter 6 so that the unsatisfactory abutment heretofore used to engage the forward part of the heel can be dispensed with and the clamping of the heel can be effected by a single operation.

I claim:

The herein-described heel clamping means consisting of upper and lower plates disposed in substantially the same vertical plane and having the edge portions thereof curved and adapted to fit in the crease between the heel seat and the heel of a shoe, the lower of said plates being stationary relatively to the upper of said plates, a pivotally mounted lever on which the upper of said plates is mounted, said plates being provided with lateral projections adjacent

to and substantially parallel to the edge of the curved edge portions of the plates, and teeth arranged longitudinally on said projections and adapted to engage the heel to prevent forward movement of the heel when the latter is moved against a cutter, said teeth provided with pointed ends which terminate

short of the edge of the curved edge portions of the plates.

In testimony whereof, I have signed my name to this specification at Los Angeles, county of Los Angeles, State of California, this 21st day of September A. D. 1915

WILLIAM J. NESBITT.

Copies of this patent may be obtained for five cents each, by addressing the "Commissioner of Patents, Washington, D. C."
